MULTIPLEX TELEVISION SYSTEM

Ralph W. Bumstead, Westfield, N. J.

Application April 20, 1935, Serial No. 17,454

18 Claims. (Cl. 178—6.8)

This invention relates to television systems and more particularly to a device for the dissemination of news items and other pieces of intelligence.

5 It is a prime object of my invention (1) to provide a system of multiplex transmission and reception of picture images over a single channel of communication. Other objects are, (2) to provide a device for the dissemination of news 10 items and other pieces of intelligence; (3) to enable the recipient of a train of signals representing multiplexed picture images to select a portion thereof for control of an image producing device while suppressing the effects of picture signals 15 unrelated to the image which it is desired to view; (4) to provide at a transmitting station suitable means for forming on a screen an image constituting interwoven character images, and for so scanning the images that picture signals 20 representing multiplexed pieces of intelligence may be transmitted over one channel of communication; (5) to embrace in the useful apparatus of a transmitting station a keyboard, a storing mechanism operable from the keyboard, and a 25 time controlled news reviewing device by which different divisions of the storing mechanism may be successively and periodically brought into operative association with an image projecting device.

30 My invention has particular utility in a system for the dissemination of intelligence such as as stock and commodity quotations, game scores, and for producing word pictures having any desired news significance. The scope of the invention is, however, by no means limited to the fields of usefulness above indicated. Other useful applications will readily suggest themselves to those skilled in the art.

When the system of my invention is to be used 40 for quoting stock market prices and the like, it is preferable to employ a storing mechanism in which the transactions may be tabularly set up as on a quotation board. For my purposes, however, it is unnecessary that the prices should be 45 made visible in the storing mechanism itself. It would be possible, of course, to post prices on an automatic quotation board of well known type and then to set up in front of such a board a television viewing and scanning device of any well 50 known type such as would compose a train of picture signals representing an image of the quotation indicators or any portion thereof. Such an arrangement would, however, be encumbered with various disadvantages and would not utilize 55 the signalling channel at maximum efficiency;

primarily due to the fact that a very considerable portion of the picture area (the spaces between the characters and between the lines) would have no significance. Hence I find it preferable to provide a screen on which may be projected different patterns representing interwoven images of the characters used to display the quotations or other news items. The elemental areas constituting character images may, if desired, be fitted together closely, like blocks in a mosaic. Substantially the entire screen area is then covered with significant elemental light and dark areas, so that, when the image thereof is "sensed" by photo-electric scanning means, the resulting picture signals will be substantially continuously 15 significant. That is to say, there will be a minimum of time wasted by scanning background areas.

In order to produce a suitable background on the receiving screen so that the character images 20 may be re-formed legibly and distinctly, I preferably provide a novel system of deflecting circuits for a cathode ray tube which is comprised in the receiving apparatus, all as will be fully explained hereinafter.

A feature of my invention which greatly adds to its utility is that it embodies means enabling anyone at a receiving station to review periodically and at frequent intervals the progress of the transactions in any particular security or 30 group of securities without asking for special service as is now required in the case of inactive stocks. By multiplexing methods the signalling channel may be so utilized as to convey signals for quotations in far greater number than the 35 number it would be possible to read before new quotations were made available. Hence I preferably provide selective means at each receiving station whereby any desired train of related signals may be utilized to the exclusion of those not 40 desired. The various stocks are then grouped according to some predetermined classification, so that, at a moment's notice, a group-selecting key may be depressed at the receiver, thereby to properly condition the receiving apparatus for 45 accepting the desired signals and for displaying the desired items on a picture reproducing screen.

Another feature of my invention is that by suitably coordinating the operation of a price-storing mechanism (a master quotation board) 50 with a time controlled program device, it is possible to review the price fluctuations of the very active stocks at very frequent intervals, say twice every minute; the less active stocks at less frequent intervals, say once a minute; and the in- 55

active stocks less often than that, say at intervals of three minutes, five minutes or ten minutes, depending upon the number of stocks in the entire list to be quoted. Upon connecting a given 5 section of the price-storing mechanism with the transmitter, a comprehensive picture of the market for any stock up to the minute may be obtained. Such a picture preferably includes, according to present practice, the Previous day's 10 closing price, and prices for the Opening, High, Low and Last transactions. In addition thereto I may, if desired, display a quantity representing the total number of shares in units of 100 shares sold up to the minute of display of the particular 15 stock quoted.

My invention in its broader aspects may include any of the features hereinabove set forth and many others as well. The scope of the invention is by no means limited except as defined by the 20 appended claims. In the detailed description to follow I have illustrated the principles and practice of the invention in respect to a preferred embodiment. It will, therefore, be understood at the outset that other embodiments readily suggesting themselves to those skilled in the art may properly be comprehended within the scope of the invention as claimed.

In the drawings:

Figure 1 shows somewhat diagrammatically 30 and somewhat in perspective a group of apparatus units suitable for transmitting picture signals representative of multiplexed character images,

Fig. 2 shows a fragment of the transmitting 35 screen on which may be projected the multiplexed character images,

Fig. 3 shows a front view of a cathode ray tube on which selected character images may be received,

Fig. 4 shows diagrammatically how different 40 picture images may be simultaneously reproduced on different receiving screens in response to multiplexed signals,

Fig. 5 shows certain details of the electrical 45 system at the transmitter,

Fig. 6 shows certain wave shapes useful in the sweep circuits of a cathode ray tube, and in otherwise controlling an electron beam therein,

Fig. 7 is a circuit diagram of a picture selecting 50 and reproducing device; and

Fig. 8 is a sectional view of one of the character image projectors which may be used at the transmitting station.

THE TRANSMITTER

Referring first to Fig. 1, a television transmitter 10 is shown with its optical system including a lens 12 which may be caused to focus an image of the screen 14 upon a photo sensitive surface (concealed within the housing of the unit 10) to be scanned by a cathode ray according to the well known teachings of the art. It is immaterial whether the screen 14 be made opaque and viewed from a position on the same side thereof as that 60 from which the light beams are projected thereon, or whether the screen 14 is made translucent so that it can be viewed from the rear as shown in the figure. The only difference between these two alternative arrangements is that the images 65 as projected by different projectors 15 would in the one case be positive images and in the other case be mirror images. The transmitter 10 is provided with "sweep-circuits" which introduce both horizontal and vertical deflecting components into the electron beam scanning opera- 70

tion. The number of scanning lines necessary to completely sweep the photo-electric image screen is of importance, however when carrying out my invention. This is true for the reason that on the screen 14 I preferably form an image pattern 5 made up of elemental light and dark areas each of which has definite significance when coordinated with the others. Each of the horizontal rows of such elemental areas preferably represents a scanning line. The cathode ray tube 10 scanning device is arranged so that the electron beam successively impinges upon these different elemental areas along each scanning line and scans different lines successively in order to sweep over the entire scanning area. Upon scanning a 15 single line the transmitter translates successively scanned elemental areas into a train of television signals. In this way each integral portion 20 of the signal train is caused to represent a single elemental area of the transmitting screen where each such elemental area is controlled by a sharply focused light beam emanating from the various light sources presently to be described. The image pattern may, if desired, be made up of interwoven character images. Any letter of 25 the alphabet and any of the numerical figures may be legibly formed by suitably disposing black and white squares in a mosaic constituted by seven horizontal rows of such squares and five squares in a row. In some instances the necessary 30 number of squares in a mosaic for a single character may be fewer than thirty-five. If preferred, the number may be made greater, either by increasing the number of elemental areas along a scanning line or by increasing the number of scanning lines. For the sake of simplicity 35 in the description of my invention I will illustrate the same generally in respect to the formation of character images covering a block of thirty-five squares, arranged in seven horizontal rows of 40 five squares each.

Now in order to provide a multiplex system of transmission of signals representing character images, it is desirable that the elemental light and dark areas of each character image be interspersed with those of other character images. To do this, each elemental area on the screen 14 is definitely assigned to some portion of a character image. Fig. 2 shows how this may preferably be accomplished. It will be noted that a fragmentary portion of the screen is indicated as having a multiplicity of elemental areas blocked out in horizontal rows representing scanning lines. Actually there are no lines on the screen but they can only be observed as boundaries between light 55 and dark areas when light is projected thereupon.

A multiplicity of light sources 15 is provided, each having a mask for composing the elements of a single character. Such a mask is shown in section at 23 in Fig. 8. The character formation 60 thereon may be obtained by perforations in an opaque sheet or by the use of a film which is for the most part opaque but which has small translucent spots thereon arranged so as to form the elements of a character image. On the screen 65 the character elements are spaced apart so that intervening areas may be occupied by light spots from other projectors. Thus, the character images become "interwoven" although they are not in any sense superposed because the screen 70 areas appropriate to one character image are mutually exclusive of the screen areas appropriate to other character images.

For illustrative purposes, I have shown groups of five elemental areas in each of three horizon- 75

tal rows bounded by heavy lines of reference. These fifteen elemental areas are each assigned to corresponding elemental areas of fifteen different character images. Their light and dark values are each under control of different groups of image projectors 15, and the control of each is, therefore, independent of that for the others. However, it is not necessary to provide as many projectors as there are elemental picture areas to be illuminated. Each projector is equipped with a film or mask by which a multiplicity of light beams may be projected on the screen so as to compose a complete character image. It is optional whether the film or mask in each projector be disposed so as to project a positive or a mirror image on to the screen, except that in the one case and screen 14 would be made opaque and would be viewed from the side on which the light is projected, while in the other case the screen would be made translucent and would be viewed from the opposite side. Such beams may be of circular, elliptical or rectangular cross section, but generally speaking, they are discrete in order that there may be no overlapping of elemental portions of different interwoven character images.

It will be seen from the foregoing description that various character images may be outlined upon the screen by focussing sharp pencils of light upon different elemental areas thereof. Each of the projectors 15 controls as many as thirty-five such elemental areas. Different projectors 15 may, however, be illuminated simultaneously and caused to project "interwoven" images upon the screen without overlapping. The method of obtaining this result is to carefully aim each projector 15 so that corresponding portions of different character images will have a slight horizontal lead one beyond another and also a corresponding vertical angular variation in order to satisfy the condition that different scanning lines of the entire screen area should be appropriate to different groups of image projectors.

From the foregoing description the method of interweaving the elemental areas of fifteen different character images has been illustrated. The arrangement of the projectors is such that they may be selectively illuminated for the purpose of variably displaying different character images. If, therefore, a space is to be reserved on the screen for displaying letters of the alphabet, then, preferably, twenty-six projectors will be focussed on identical spots of the screen and any one of the twenty-six projectors when illuminated will display its respective letter. If figures only are to be displayed on certain areas then the number of projectors to be alternatively actuated will be ten. Only seven or eight projectors are necessary in reference to the display of character designations representing "eighths," according to current practice in this country when quoting stocks.

As illustrated in the drawings, a very large number of projectors is to be employed for controlling the formation of a multiplexed character image pattern on the screen. In this particular embodiment it is provided that quotations for fifteen different stocks shall be simultaneously projected on the left half of the transmitter screen and for fifteen other stocks on the right half. The group of quotations for a single stock is displayed on seven character-lines, including a line for the stock abbreviation. Each character line has the height of twenty-one scanning lines, although only seven scanning lines are used in forming a character image. The interspersed

scanning lines are used for the multiplexing of different character images. The quotations usually comprise tens- and units- digits, and a digit representing a fraction. A hyphen (-) may be displayed when the quotation is "flat." The other fractions are usually indicated as 1, 2, 3, 4, 5, 6, and 7, the denominator /8 being understood in each case. If a stock is quoted between 100 and 200, the tens-figure can be represented (on the receiving screen) in a space the width of which comprehends only three elemental areas. This leaves room to show a hundreds-figure "1" as a vertical line at the extreme left of the space ordinarily occupied by the tens-figure. If other hundreds-digits are to be indicated, they can usually be provided for by showing two or more dots, vertical dashes, or combinations thereof in place of the "1" which indicates "100."

The seven horizontal rows of characters for a stock group may, if desired, comprise quotations arranged thus:

Previous close	25
Stock abbreviation	
Opening	
High	
Low	
Last (or Market)	25
Volume ("00" omitted)	

If, as shown in Fig. 3, the prices of two stocks are to be displayed simultaneously on a receiving screen, then, preferably, the width of the screen will be divided into six character spaces. On the transmitting screen each of these character spaces is again divided laterally into twenty-five elemental areas, so that as many as 150 elemental areas exist on each scanning line. Five character images are interwoven laterally and three vertically on the transmitting screen, thus providing for the multiplexing of fifteen different picture images.

The arrangement of projectors 15 and of screen area division thus far described may be tabularly summarized thus:

Horizontal aspect	45

Each scanning line is occupied by 150 elemental areas, of which 5 are appropriate to each of 30 characters; there being 5 characters interwoven laterally, 3 characters per stock quotation and two stock groups separated by the vertical center line of the screen. A synchronizing signal precedes and follows the transmission of a train of signals representative of the elemental light and dark areas along each scanning line.

Vertical aspect	55

There are 168 horizontal scanning lines occupied by seven character bands plus one band the time of scanning which is utilized for transmitting a frame synchronizing signal. Each character band occupies 21 scanning lines. So also does the frame synchronizing band, the time component of which is taken up by the return stroke of the vertical beam deflection in the scanning operation. Three character images are intermeshed vertically and each character image is formed by light and dark elemental areas along seven scanning lines.

The picture frame	70

As constituted at the transmitter, eighteen numerical image patterns are simultaneously arrayed on the screen for each stock group. These eighteen image patterns are divided into six lines of three figures each representing the tens, units

and fraction digits of different quotations on each line. The quotations usually provided on an indicator of this type include the following:

Previous closing price, open, high, low, market (or last), and volume. The last mentioned quotation may, if desired, express hundreds of shares of stock sold up to the moment of display of the prices. From one to three letter-images are also arrayed along one character band to represent each stock abbreviation. Thirty stock groups within the picture frame $\times 21$ character images per stock group $\times 35$ elemental areas per character = 22,050 elemental areas on the screen.

A group of twenty-eight projectors is adequate for displaying any possible quotation from $\frac{1}{8}$ to 99%. In order, therefore, to provide complete interchangeability of price images for thirty stock groups, each group comprising five prices, $5 \times 30 \times 28 = 4200$ projectors are needed. If volume of transactions is also to be indicated, $30 \times 30 = 900$ additional projectors would then be arranged to cover the bottom character line of the picture.

The image pattern for all the interwoven letters of thirty stock abbreviations may, if desired, be fixedly obtained by using a stencil or mask in a single projector for this purpose. Such projectors, however, will be multiplied in number by the number of different stock groups to be successively displayed during a cyclic survey of all the stocks whose prices are stored in the intelligence storing device 16. In the illustrative embodiment herein shown, twenty such changes of scene are provided for. Hence there are twenty projectors for the interwoven letter images representing stock abbreviations. The 22,050 elemental screen areas may therefore be controlled by $4200 + 900 + 20 = 5120$ projectors, if the news disseminating system is made as herein illustrated.

Referring to Fig. 8, a typical projector 15 is shown swivelled on a support 17 which has a yoke 18 with bearings 19 in which two lugs 20 may rest for vertically adjusting the aim of the projector. The axis of the projector may therefore be oriented both horizontally and vertically in order that its projection of light beams may be properly aimed at the appropriate elemental areas on the screen 14.

The projector comprises a lamp 21, lenses 22 for diffusing the light uniformly over the area of the image film or mask 23 and a lens 24 for focussing the image on the screen 14. Suitable adjustability of these elements with respect to one another is obtained by mounting the lamp 21 on a holder 25 and the lens 24 in a holder 26. Both of these holders slide telescopically within the cylindrical housing 27. Binding screws 28 serve to maintain all adjustments, once they are made.

Fig. 2 illustrates further how the interwoven image patterns may be produced by the cooperation of different projectors. In each rectangle comprehending fifteen elemental areas the spot in the upper left hand corner is assigned to one message which will be termed the A₁ program. On the same scanning line four other picture programs A₂, A₃, A₄ and A₅ are arranged in succession. On the second scanning line are the five programs B₁ to B₅, inclusive, and on the third scanning line programs C₁ to C₅, inclusive. It will now be seen that the thirty-five elemental areas reserved for the representation of each numerical character image in program A₁ are controlled by not more than ten selectively actu-

ated projectors 15, while similar projectors are arranged to control corresponding elemental areas of the other fourteen programs. Thus, on the fragmentary screen area of Fig. 2 certain numerals are represented by distinguishing marks merely to denote, by way of example, the spots that would preferably be illuminated for showing—

Numeral	Program	Mark
4	A ₁	X
2	A ₁	O
1	C ₁	■

The angle of incidence of the light beams as projected upon the screen 14 should be held as closely as possible to 90°. Nevertheless, departures from that angle are necessitated by the fact that a plurality of projectors 15 is aimed to cover a mosaic inclusive of many interwoven character images. To compensate for possible distortion of the screen image, the image on the film or mask 23 within the projector may be purposely distorted. One method of doing this is to take photographs of perfectly formed character image subjects with a camera set in the same position relative to the subject as a given projector will occupy relative to the screen. The resulting film, or a stenciled mask patterned therefrom, may then be used in the correspondingly situated projector. The elemental areas of each of the interwoven character images should therefore occupy their proper positions on the mosaic in perfect registration.

THE INTELLIGENCE STORING DEVICE

The multiplicity of projectors is preferably controlled, according to my invention, by a system of rotary switches 30, as shown in Fig. 5. Each switch, if it is to select a numeral to be imaged on the screen, is provided with eleven contact segments 31, one segment being dead, and the remaining segments being connected respectively to different feeder wires 32 each leading to an appropriate lamp 21 in the projector system.

The switches may be arranged in groups, in the same manner that rotary drum dials are grouped to indicate the desired digits and fractions of stock quotations. The wiper element 33 of each switch may be set and reset as often as necessary to store the intelligence which is to be communicated by a cyclic review of the price fluctuations.

The wipers or selector-rotors 33 may be actuated from a keyboard 34 (Fig. 1) according to a "System for remote control of stock quotation boards" as shown in my co-pending application Serial No. 584,431, filed January 2, 1932, or other well known means may be employed. U. S. Patent 2,052,539 granted August 25, 1936 to Frischknecht et al. also shows a quotation board system having a keyboard and selective means for controlling rotary switches, indicators, and the like. No specific actuating mechanism is herein shown because, for the purposes of this invention, it is merely necessary to indicate that any suitable means, such as a keyboard, a perforated tape transmitter, or the like, may be associated with the rotary switches 30 for causing them to distribute power along various circuits 32 at different times, thereby to control the lighting of the projector lamps 21.

According to the herein shown system for continuously cyclic survey of all the prices "posted" 75

on the switches 30, it is preferable that each of the feeder wires 32 be connected in multiple to corresponding segments 31 of a plurality of switches. In order to prevent "feed-back" and uncontrolled dissipation of energy through the wipers of switches other than those selected from time to time to assume control, rectifiers 33 may be placed in series with each wiper 33. Such rectifiers may be of the dry copper-oxide plate type, and because of their low cost, their use is preferable to an alternative arrangement in which an individual make-and-break device would be necessary in the circuit for each wiper 33.

All of the wipers 33 to be simultaneously fed with current at any one moment may be permanently connected through a conductor 36 to one segment 37 of the timing control switch 40. Some of the conductors 36 may, however, be connected to a plurality of segments 38 or 39 in order that the frequency of feeding current to the storage switches may be greater than in the case of the conductors leading to segments 37. The object of this arrangement is to provide a review of quotations for the very active stocks at intervals, say, of thirty seconds; for the less active stocks once every minute; and for the generally least active stocks once every five minutes. In the circuit diagram of Fig. 5 such a program is indicated, where the control switch has a total of fifty segments (arranged in two semi-circular banks as is usual) of which, the segments 37 lead to the storage switches for stocks that are to be quoted once every five minutes; while segments 38 lead to the storage switches for the "once-a-minute" quotations and segments 39 to switches for the "twice-a-minute" quotations. Only one timing control switch 40 is required for the entire system.

In order that the drawings might not be confusingly elaborated by the number of lines for showing the multiplicity of conductors and rotary switches 30, the general scheme has been illustrated by simply showing the connection to a few such switches. The two groups each comprising three vertical columns of switches 30 are typical of as many switch groups as there are stocks to be quoted. However, the system as herein contemplated is of such capacity as to cover 600 stocks, and the timing control switch 50 makes fifty changes of scene within a five minute period, allowing six seconds for each display period. During the five minute period, quotations for certain stocks are to be communicated by ten showings on the screen, others by five showings, and still others only once. This is all provided for by the arrangement of the twenty conductors 36, to the fifty segments 37, 38 and 39.

Considering that there are three numerical designations per quotation, six lines of quotations (including the "volume") and fifteen interwoven patterns of the character images and two stock groups to be displayed side by side on each "program," it will be seen that the number of rotary switches to be simultaneously connected with a power source through the timing control switch 40 is $3 \times 6 \times 15 \times 2 = 540$, and for the twenty conductors 36 which are successively selected by the operation of the switch 40, the number of switches 30 to be fed with power is 10,800.

Each of the twenty conductors 36 is also branched to an abbreviation projector, twenty of which are to be understood as comprehended within the rectangle 15A. It will be recalled that one interwoven image pattern for thirty stock abbreviations may be displayed on the

screen 14 by a single projector 15, provided the selection of stock groups to be simultaneously quoted remains fixed.

Thus with each change of scene that produces a multiplexed image pattern according to the latest settings of the rotary switches in the price storage mechanism, an identification of the quotations is obtained by appropriate simultaneously projected images of the stock abbreviations.

The means for actuating the timing control, or program switch 40 includes preferably a clock 41 having a contact device for periodically closing a circuit from the power supply 42 to the motor-magnet 43. The two wipers 44 are mounted on one shaft, as indicated by the broken line joining their rotational axes. The shaft also carries a ratchet wheel 45 with which a pawl 46 engages. The pawl is actuated by the armature 47 of the magnet so as to drive the wipers step-by-step into contact with successive segments. The clock impulses may be of brief duration, say $\frac{1}{20}$ sec., more or less, and the wipers may be permitted to rest on each contact for about six seconds to permit of the persistence of a given image on the receiving screen for sufficient time to comprehend the same.

Due to the considerable wattage of the power for lighting as many as 540 projector lamps simultaneously, it may be desirable to employ relays, either electromagnetic, mercury-pool, or electronic for feeding current to the conductors 36. If this is done, only a feeble current would be required to pass through the wipers 44. It is also desirable that the connection between the power supply 42 and the wipers 44 be broken during the brief interval of stepping from one segment to another. Such arrangements have not been shown in the drawings because they constitute obvious expedients well known in the art, and would only introduce unnecessary complications into the diagram.

The photo-electric camera 10 which senses the images formed on the screen 14 has its own photo-electric screen 48 on which corresponding images are formed. The electron beam scans these images in a line-for-line manner under control of horizontal and vertical deflecting circuits 49 which are fed with suitable saw-tooth waves from the generator 50. The scanning lines followed by the electron beam must "track" with the lines of elemental light and dark areas of the character images in order to avoid confusion of signals. This can be accomplished by suitably focussing and locating the optical image on the photo sensitive surface 48. The generator 50 supplies the necessary synchronizing impulses with which the picture signals are coordinated in the usual manner.

Apparatus including an amplifier and transmitter 51 may be of any well known type. It is adapted to send out the synchronizing and picture signals over a single channel of communication under joint control of the photo electric camera 10 and the scanning frequency generator 50. The signals may be impressed as modulations on a carrier wave, preferably of ultra-high frequency, and then radiated through space. Or, the signals may be transmitted by wire or cable.

Due to the fact that in this system a persistence of each image for a period of preferably six seconds is provided for, it may not be necessary to repeat the scanning operation as rapidly as would be the practice in transmitting moving pictures. Objectionable "flicker" effects can be

avoided in the display of the received image if the "decay period" for such an image formed on a fluorescent screen is prolonged, according to known methods.

5 THE RECEIVER

At any one or more points of reception apparatus may be employed which reproduces any one of the multiplexed picture programs independently of the others. Also, a choice of the 10 programs may be had at any receiving station which is changeable thereat under control of an observer during the periods of transmission.

Fig. 7 shows apparatus to be used at each receiving station. First there is a conventional 15 radio receiver 60 for amplifying and detecting the signals. The output energy is distributed three ways—(1) as "frame"-frequency synchronizing impulses, (2) as scanning line frequency synchronizing impulses, and (3) as picture signals. Tuned filters 61 are provided for passing the synchronizing impulses under control of which saw-tooth waves are generated for vertically and horizontally deflecting the electron beam in a cathode ray tube.

20 A program selector switch 62 follows the filters 61. In the illustrative embodiment herein shown this switch is manually controlled and has fifteen positions to cover a choice of programs A₁ to A₅, B₁ to B₅ and C₁ to C₅ as heretofore described. The 25 choice is made by introducing more or less delay into the generation of impulses by which all of the picture signals are suppressed except those which are to form the selected picture image. The generation of saw-tooth waves for the sweep-circuits is also conveniently delayed, though it 30 may not be essential to do so.

35 The selector switch 62 comprises a brush carrier 63 which has two brushes 64 insulated one from the other. Contact segments 65 are fed with frame-frequency impulses at, say, 16 cycles per second. Segments 66 are likewise fed with impulses at a line scanning frequency of say 2,688 cycles per second.

40 No delay is introduced into either of the circuits established by setting the selector switch into the first position. The next four segments 45 66 (reading from left to right) lead respectively to different delay networks L₁ to L₅ for differentially delaying the generation of line-scanning waves. The first five positions are for horizontal 50 shifts of the picture frame independently of the picture signals. The delay network utilized in each case is such as to render effective every 55 fifth elemental area signal, starting either with the first, second, third, fourth, or fifth signal from the beginning of each scanning line.

60 The other delay networks F₂ and F₃ may be used for delaying the frame frequency scanning operation by as much as one or two line-scanning time-intervals respectively. It is to be understood that these delay networks function not only to shift the scanning lines and the vertical framing of the picture with respect to the picture signals, but also (as will hereinafter be 65 shown) to vary the relation between the impulses transmitted through the filters 61 and the picture-signal impulses, so as to suppress all of the latter with the exception of those that are to be 70 utilized in the formation of elemental light and dark areas of the selected picture.

75 In the first five positions of the selector switch 62 no delay is introduced into the synchronizing impulses which may be fed through the conductor 67 to the frame-frequency saw-tooth wave

generator 68. The next five positions of the selector switch are such as to feed the frame-frequency synchronizing impulses through the delay network F₂ and thence to the generator 68, thus obtaining a delay in the vertical scanning operation of

$$\frac{1}{2688} \text{ sec.}$$

In the remaining five positions of the selector 10 switch 62, the delay network F₃ is brought into play, thus doubling the delay period and making it

$$\frac{1}{1344} \text{ sec.}$$

15 The segments 66 of the selector switch are so connected with the delay networks L₁ to L₅ inclusive and to a conductor 70 which shunts out these delay networks that the line scanning operation may be started either with no delay or with different delays amounting to one or more periods of an elemental-area signal. In the illustration given, such a signal period may be of the order of

$$\frac{1}{403200} \text{ sec.}$$

20 If, therefore, the delay action of the networks L₂ to L₅, inclusive, corresponds respectively with the 25 time values for from one to four elemental area signals, these values will be as follows:

$$L_2 = \frac{1}{403200} \text{ sec.} \quad L_3 = \frac{1}{201600} \text{ sec.}$$

$$L_4 = \frac{1}{134400} \text{ sec.} \quad L_5 = \frac{1}{100800} \text{ sec.}$$

30 A cathode ray tube 75 is provided having the usual electrodes for controlling the emission of 35 electrons in a beam against a fluorescent screen 76. This tube is preferably provided with vertical deflecting coils 77 and electrostatic plates 78 for horizontal deflection. In place of the 40 coils 77, electrostatic plates may be used if desired. The deflecting coils 77 are variably energized through a circuit 79 which is fed with power from a source 80 through the choke 97, across which variations in potential are developed when the electron tube 81 becomes more or less conductive. The return circuit from the 45 coils 77 leads to ground (the negative side of the source 80 being grounded) through a portion of the potentiometer 73 and, for surges, through the 50 capacitor 71.

55 The input circuit of the tube 81 includes a control grid 82, a grid bias resistor 83, biasing battery 84, and the cathode 85. The tube 81 is controlled by the saw-tooth wave generator 68, 60 which may be of any well known type. Fig. 6 shows an outline of a wave 86 which may be so generated and impressed across the capacitor 81 for controlling the tube 81.

65 In order that suitable separation between certain of the scanning lines may be obtained for producing a background effect between the character lines, I preferably cause the vertical scanning operation to be produced in successive steps as shown in the curve 88_v of Fig. 6. This is 70 accomplished by superposition upon the frame-frequency wave 86 of another wave 89 of saw-tooth shape but inverted. There is considerable choice of well known means for obtaining such superposition, or mixing of two waves. I have shown, by 75

way of example, how the saw-tooth wave 88 may be impressed upon the screen grid 90 of the tube 81. The circuit for this purpose may be traced starting from a frequency multiplier 81 which produces the eighth harmonic of the frame-scanning frequency, in order that there may be eight groups, or bands of scanning lines, the lines of each band being crowded together so as to create background bands constituting horizontal character-line spaces on the screen area. The frequency multiplier 81 feeds energy to a saw-tooth wave generator 92 which provides impulses at the rate of 128 cycles per second.

Although I have shown only seven character lines on the screen 16 of the cathode ray tube 75, it will be understood that a certain time allowance must be made for the return stroke of the vertical deflection. I have conveniently figured this return stroke as taking place during the transmission of 21 blank scanning lines, equivalent to a band of scanning lines for one character-line, or character height. It is for this reason that I preferably use the eighth harmonic of the frame scanning frequency to control the generation of saw-tooth waves as shown by the wave pattern 89 in Fig. 6. I have not shown eight such waves as occupying the time interval of one frame-scanning cycle, although, for this purpose, the showing might have been more accurate; but these curves 86, 88_v, 88_h, and 89 are referred to in connection with the description to follow relative to the horizontal scanning operation. However, the superposition of two such waves 86 and 89 to form a composite wave 88_v may readily be understood from the appearance of the wave patterns given in Fig. 6, where t_1 represents the time constant of the vertical scanning cycle, or (from another aspect) of the line-scanning cycle, while t_2 represents the time constant of the saw-tooth wave to be superposed upon one of these frequencies in either case.

The wave produced by the generator 92 may be impressed across a capacitor 93 and thence to the control grid of an electron tube 94. The anode circuit of the tube 94 may be fed with energy from an intermediate point 95 on the source 80 and through an inductive impedance 96. The anode 98 has a connection to the screen grid 90 of the tube 81.

The operation of the vertical deflecting circuit may now be described as follows:

Assuming that the gradual slope of the curve 86 is represented by a positive impulse impressed across the capacitor 87, it will be seen that the tube 81 becomes more and more conductive until suddenly this wave is interrupted completely and the tube is biased to cut-off. At that moment the anode potential will be suddenly built up to full positive value, due to the saturation of the inductance 97 and to the fact that the tube 81 affords a substantially infinite impedance to the further flow of current. The effect is to produce a strong and sudden reversal of current flow in the deflecting coils 77 for producing the return stroke in the vertical deflection of the electron beam in the cathode ray tube 75.

While the current is gradually being increased in value in the tube 81, that increase may be made at two different rates, one while certain of the line scanning operations are being effectively performed and another for causing separation between the bands of scanning lines. This is accomplished through the use of the saw-tooth wave generator 92 which may be assumed

to feed current positively across the capacitor 93 and with gradually increasing intensity so that the tube 94 becomes gradually more conductive and the potential on the anode 98 gradually falls. This likewise gradually lowers the potential on the screen grid 90 and slows up without nullifying the increase of conductivity of the tube 81. When, however, the tube 94 is suddenly biased to cut-off by the steep return stroke of the wave 89, then the anode 98 and 10 the screen grid 90 become suddenly more positive and the shape of the wave 88_v is caused to be formed into steps. This provides the desired band separation between successive groups of 21 scanning lines. 15

Referring now to the horizontal, or line-scanning operation, the frequency for synchronizing the waves generated by the saw-tooth generator 69 is obtained directly from the line scanning frequency signals over the conductor 70 or 20 through any one of the delay networks L₂ to L₅ inclusive. This frequency is assumed to be of the order of 2,688 cycles per second. Here again, the output energy from the generator 69 may be assumed to be increasingly positive as the saw-tooth 25 wave 86 slopes gradually upward. This impulse increases the conductivity of the discharge tube 100 in the same manner as was described above in respect to the operation of the tube 81. The tube 100 also has a screen grid 101, which is connected to the anode of an electron tube 102. The tube 100 may be caused to operate above and below the cut-off of its characteristic in the same manner as hereinabove described in respect to the tube 81. The anode of the tube 10 is, however, preferably fed with current from the source 80 through an inductive impedance 103. The step formation of the wave generated by superposing the two waves which are the respective outputs of the saw-tooth wave generator 69 and 40 of the saw-tooth wave generator 99 may be as shown in the wave pattern 88_h of Fig. 6. This wave may then be impressed across two capacitors 104 and thence to one of the horizontal deflecting plates 78 of the cathode ray tube 75. The 45 other of the deflecting plates 78 is connected to the lower end of a resistor 105 and to a capacitor 106 which may be energized contraphasally to the capacitors 104 by virtue of the delay action introduced through the inductive impedance 107. 50 The circuit arrangement of the elements 104, 105, 106 and 107 is not new and no claim is herein made to this circuit arrangement as such. One of the features of the circuit however resides in the provision of a central tap on the resistor 105 55 from which a connection may be made to the most highly positive anode 108 in the cathode ray tube 75. This last mentioned connection serves to maintain suitable balance in the horizontal deflection forces so that pictures may be 60 properly framed on the fluorescent screen 16.

The frequency of the saw-tooth wave generator 99 is preferably six times that of the generator 69 in order that six characters and six character separations may be obtained and suitable 65 background areas formed between the characters along a character-line. Hence I provide a frequency multiplier 110 to produce the sixth harmonic of the line-scanning frequency. This multiplier receives its energy from the line scanning frequency impulses at the rate of 2,688 cycles per second. The output energy from the frequency multiplier is in the form of sharply peaked impulses at the rate of 16,128 per second. In this case, therefore, the output waves from 75

the saw-tooth wave generator 99 have a time constant

$$t_2 = \frac{1}{16,128} \text{ sec.}$$

5 as against the line scanning time

$$t_1 = \frac{1}{2,688} \text{ sec.}$$

- 10 The cooperation of the tubes 100 and 102 for producing a wave of the pattern shown at 88_a in Fig. 6 is the same as was previously described in respect to such a wave 88_v for the vertical scanning operation. The two waves 88_v and 88_h differ only 15 in their frequencies and in the matter of how many steps occur within one cycle of each fundamental frequency, whether of the frame scanning or the line scanning circuits.

The picture signals from the receiver 60 may be 20 directed through a conductor 115 to a compensating delay network 116 and thence to a control grid 117 of an electron tube 118. The control grid 117 is preferably one of a pair of co-planar grids, the other grid 125 being employed also as 25 a control grid. The purpose of the compensating delay network 116 is to adjust the phase of the picture signal impulses with respect to the phase of the signal-selective impulses as derived from the synchronizing signals passed through 30 the filters 61. It may well be seen that, due to the complexity of the filter circuits and the delay networks, it may not be possible to obtain this phase agreement but for a compensating delay network. The constants of such a network, however, may be maintained fixed, once they are suitably established. The output circuit of the electron tube 118 includes an anode source 119 and a 35 resistor 120 on which it is preferable to provide a tap 121 leading to a capacitor 122. The control grid 117 may be suitably biased by means of a grid resistor 123 and a biasing battery 124. A second control grid 125 is similarly biased by means of a grid resistor 122 and the biasing battery 124. The two grids 117 and 125 may be normally biased so far below the cut-off point on 40 the tube characteristic that the tube will become conductive only when positive impulses are simultaneously impressed upon both grids. If then, a signal representing an elemental light area is impressed as a positive impulse upon grid 117 and simultaneously a sufficiently positive impulse is impressed upon the grid 125, then the tube 118 will operate to pass the selected picture signal along to the cathode 130 of the tube 75. In this case the light area signals produce an anode 45 current flow in the tube 118. The potential on the anode 111 will be lowered, thereby causing a negative surge across the capacitor 122 which lowers the potential of the cathode 130 in the cathode ray tube 75. The control electrode 131 of this tube may be grounded and through the use of a tap 132 on the potentiometer 133 leading to one end of a biasing resistor 134 a suitable 50 negative bias may normally be maintained on the control electrode 131. When, however, a negative picture signalling impulse lowers the potential on the cathode 130, then the control electrode bias is reduced and a volley of electrons is emitted from the cathode and toward the fluorescent screen 76 at some point determined by 55 the time components of the horizontal and vertical deflecting circuits. The use of the so-called electron gun in the cathode ray tube 75 is well known and needs no detailed explanation here except by way of mentioning that its control is 60 rendered suitably effective by the aid of focus-

sing and accelerating electrodes 135 and 136 respectively and by the anode 108. All of these electrodes receive their polarization charges from a high voltage supply 137. The potentiometer 133 may be placed across the terminals of the voltage supply 137 and taps off the potentiometer may be adjusted to supply suitable potentials to each electrode.

According to a modification which will be apparent to those skilled in the art, the tube 118 10 may be made normally conductive in the absence of light area signals and when such signals are to be suppressed. In this case the capacitor 122 would be connected to the control grid 130 and the electron gun would be caused to discharge 15 under control of positive impulses as occasioned when the grids 117 and 125 are simultaneously more negatively biased.

It was mentioned above that the operation of the tube 118 for transmitting picture signals to 20 the cathode 130 of the cathode ray tube may be made contingent upon the impress of a positive charge upon a second grid 125. It will now be shown how this positive charge may be obtained for the purpose of rendering effective only those 25 picture signals which are desired to form a given selected picture.

A frequency multiplier 140 is fed with impulses from the output side of the frequency multiplier 91. A seventh harmonic of the eighth harmonic 30 of the frame frequency is thus obtained, this, as illustrated, being 896 cycles per second. These impulses may be fed to the control grid 142 of an electron tube 141. This tube is normally biased to permit current flow therein but when a sharply 35 peaked negative impulse is delivered to its control grid 142, the tube is biased to cut-off and its anode potential is raised to a point where a strong positive pulse will be delivered across the capacitor 143 and thence to the control grid 125 40 of the electron tube 118, provided such impulse is not dissipated through a shunt circuit which includes the capacitor 144 and the space current path through a companion tube 150.

This electron tube 150 may be controlled in a 45 similar manner through frequency multipliers 140 and 151. The frequency multiplier 151 delivers sharply peaked impulses which are the fifth harmonic of the impulses delivered by the frequency multiplier 140. These impulses, in turn, have 50 been shown to be the sixth harmonic of the line scanning frequency. Hence the frequency delivered by the frequency multiplier 151 is of the order of 80,640 cycles per second, or one impulse 55 for every five elemental area picture signal impulses.

If, now, it be considered that the electron tube 150 becomes biased to cut-off once for every fifth picture signal it, too, will deliver a strong positive impulse to the control grid 125. The potential 60 derived from a battery 155 and impressed across the resistors 145 and 146 respectively may be such as to permit of the dissipation of energy in the resistor-capacitor loop including the capacitors 143 and 144 without carrying an effectively positive impulse to the grid 125, if some of this energy 65 leaks off through either one of the tubes 141 and 150 while it is conductive. If, however, both of these tubes become biased to cut-off simultaneously then both capacitors 143 and 144 would 70 simultaneously receive charges such as to raise the potential of the grid 125 high enough to render the tube 118 conductive and thereby to pass the picture signals. Thus, the tube 150 tends 75 to let pass one signal out of every five, for the 76

duration of one scanning line while its anode is lowered in potential to avoid the charging of the condenser 143 during the period of two scanning lines. It is, therefore, only the one signal out of five along a scanning line, and only such signals as occur along one scanning line out of three that become effective. Thus all signals along two subsequent scanning lines are blocked out, since they do not represent any portion of the selected picture.

The frequency multipliers 140 and 151 may be of any suitable well known type. Coupled thereto, but not shown, are suitable wave shaping devices for determining the time intervals to be taken up by the positive peaks in relation to the time components of the negative peaks, for properly controlling the tubes 141 and 150 respectively. Where inequality between the positive and negative peaks is required, this can be accomplished in a well known manner through the use of an asymmetric multivibrator. Furthermore, if desired, the wave peaks may be shaped in accordance with the requirements for limiting the effective time components thereof as shown by the curves 160 and 161 in Fig. 6.

The curve 160 represents a wave form suitable for controlling the tube 141. In this case the positive impulse has a time value of

$$30 \quad t_3 = \frac{1}{3} \text{,2,688} \text{ seconds}$$

whereas the negative peak of this wave has a time value of

$$35 \quad \frac{2t_3}{3} = \frac{1}{1,344} \text{ seconds}$$

where

$$896 t_3 = \text{one second}$$

40 The wave form as shown by the curve 161, Fig. 6, is preferably such that its positive and negative peaks have a time ratio 1:4. Since the full wave time value is of the order of

$$45 \quad t_4 = \frac{1}{80,640} \text{ sec.}$$

it will be seen that the positive peaks

$$50 \quad \frac{t_4}{5} \text{ sec.}$$

endure for a period of

$$55 \quad \frac{1}{403,200} \text{ sec.}$$

and the negative peaks persist for a period of

$$60 \quad \frac{1}{100,800} \text{ sec.}$$

65 In the foregoing description all of the circuits shown in Fig. 7 have been traced. It remains now to show by means of further wave diagrams what is accomplished by the joint operation of these circuits. Fig. 6 is again referred to. Wave form 162 represents the combined output from the two discharge tubes 141 and 150, as impressed across the capacitors 143 and 144. The broken line *g* represents the cut-off point of the negative bias applied to the grid 125 from the battery 124 through the resistor 112. The peaks *p* which lie above the level of the line *g* are obtained only when the waves 160 and 161 are positively peaked at the same time. The wave portions *k*, *m* and *n* all lie below the level of the line *g* and are, therefore, effective in suppressing the effects of the picture signals which have not been selected

according to a given setting of the selector switch 62.

The picture signals are typically represented by the curve 163. If the duration of a positive peak is for some multiple of an elemental area signal, the correct inference is that there are contiguous elemental light areas belonging to two interwoven but unrelated picture patterns. The positive picture signals are of sufficient intensity to overcome the steady negative bias on the grid 117, as indicated by the level of the cut-off line *h*, but the cut-off point of the tube characteristic is such that it becomes conductive only when the grids 117 and 125 are simultaneously raised to a potential above their respective cut-off points. 15 The wave form 164, therefore, represents the composite effect of varying the potentials on the two grids. The cut-off point of the tube characteristic is represented by the broken line *j*. Fluctuations of the composite grid bias, such as 20 the peaks *u*, which are below the cut-off point, are ineffective, but when peaks of grid bias occur as shown at *s*, then anode current flows in the tube.

The effectiveness of the delay networks L_2 to L_5 inclusive is apparent for selecting any one of five elemental area signals successively transmitted. Also, when one such signal is chosen, every fifth successive signal on the same scanning line is rendered effective. All picture signals occurring 30 during the scanning of the two succeeding lines are blocked out by the condition of conductivity of the tube 141. When, however, it is desired to select a "program" occurring on either of these heretofore rejected scanning lines, the selector switch 62 may be shifted into any one of its last ten positions, five of which bring into play the delay network F_2 and the other five of which render the delay network F_3 effective. This provides a choice of picture signals starting with the 40 second or third scanning line from the beginning of a frame scanning cycle.

In the embodiment shown, it is possible to obtain any desired selection of programs from among the fifteen multiplexed signal trains, 45 where each train of signals is understood to be related to an independent picture program. The word "program," it will be recalled, is considered apt in view of the intention to change the "scene" after every lapse of a six-second time interval, or 50 other time interval sufficient to read the message conveyed by one scene.

Fig. 3 shows, by way of example, how the characters of a selected scene may be formed on the fluorescent screen 16. Apparently the elemental 55 light areas are, in many instances contiguous, although it will be appreciated that the selected signals for controlling the actuation of the electron gun are discrete. This very desirable effect is obtained by de-focussing the electron beam in the cathode ray tube 15 so that its coverage will be equal to the coverage of fifteen elemental areas if there were to be no suppression of signals in respect to the non-selected programs. The structure of the electrodes in the cathode 60 ray tube and the choice of potentials to be applied to these electrodes may be such that the desired degree of de-focussing may be obtained, all as is well known in the art.

It is possible to practice my invention without 70 employing the very high modulation or keying frequencies shown, by way of example. Thus, if it is desired to slow up the cyclic operation of the deflecting circuits, both at the transmitter and at the receiver, this may be done without 75

loss of detail in the image pattern. The persistence of the image without noticeable flicker is the prime desideratum. Flicker effects can be overcome to a large extent by careful choice of the fluorescent material with which the screen 16 is coated. Some of these materials when electronically excited have a much longer "decay period" than others. If, therefore, the same image is to be flashed on the screen nearly a hundred times without change, rapid fading of the illuminated areas is not to be desired, but, on the contrary, a slowness of "decay" such as will retain the brilliancy of the image between successive frame-scanning operations.

15 It is known that different fluorescent substances may be used on the screen 16 for varying the color effects produced by electronic impact. Accordingly, it may be desired, in the case of quoting fractional price variation, that the character representing a fraction be shown in a color different from the color of the other characters. If this is done, it then becomes unnecessary to under-line the fractional numerators as shown at 182. Instead, it may be preferable to display 25 numerator digits for the "eighths" fully as high as the units- and tens-figures, but distinguished only by their color.

The screen 16 may, if it is to be used solely for quoting prices, be permanently marked as shown 30 at 180, as a guide to the interpretation of each line of quotations. A space between two ruled horizontal lines 181 on the screen surface may be permanently reserved for stock abbreviations. If two or more stocks are to be quoted simultaneously, as herein shown, in different columnar groups, then vertical lines may be ruled on the screen for stock group separation. All such aids to an intelligent presentation of the bare picture impressions will, of course, contribute to the effectiveness of the display without imposing further demands upon the signaling equipment.

Fig. 4 illustrates an arrangement for feeding picture signals from one receiver simultaneously to a plurality of cathode ray tubes, each of which 45 may present a program different from the others. In this case it may be desirable to provide independent selector switches and delay networks in connection with each cathode ray tube. Thus, I have shown (in front view) five such tubes and 50 have designated them B₁, A₂, B₃, A₄ and C₅, corresponding to the programs thereto allotted. The line synchronizing signals are to be understood as fed through different delay networks d, 2d, 3d and 4d for the cathode ray tubes other than B₁, 55 whereas, the latter has no such delay network because the choice of programs assignable thereto may not need to be varied horizontally of the multiplexed picture pattern, but only vertically. Each of the circuits for controlling the vertical 60 synchronizing is, however, fed through a device 170 which includes a three-point switch and two delay networks, such as F₂ and F₃. In the first position of each switch the networks are shunted out. The middle position connects network F₂ and the third position connects network F₃. It 65 will thus be seen that any one of three programs is available to each cathode ray tube, while the selection made for each tube is always different from that of the others.

70 It will be apparent from the foregoing that news can be disseminated from one transmitting station to as many receivers as are situated within range of the signals, but that means are associated with each receiver for making a de-

sired choice of programs from among those multiplexed at the transmitter.

RECAPITULATION

In the foregoing description I have set forth 5 the details of structure preferably employed for achieving certain new and useful results in the art of news dissemination. The methods adopted are replete with novelty, as will be set forth with particularity in the appended claims. Modifications of structure and of method, if adopted by those skilled in the art, may, possibly, lead to more general applications of the invention than were at first contemplated. For example, it may be found useful to provide a communication system 15 in which code signals are caused to represent successively scanned light and dark areas on a screen. These code signals may also be interwoven for the sake of rendering the intelligence quasi-secret. The method herein shown of selecting desired elements from multiplexed trains 20 of signals for reproducing a given communication at the point of reception lends itself to photographic recording of code messages and to a subsequent deciphering in any well known manner. If the number of elemental areas to be skipped in the sorting process is unknown to a person attempting to intercept a message, then the risk of unauthorized de-ciphering of the message 25 becomes negligible.

The method I have disclosed in which the entire mosaic of the transmitting screen is occupied by significant light and dark areas of an image pattern, and in which character images are disposed on said mosaic without any background 30 areas intervening, leads to a more economic use of signaling channel time than was possible when character image signals were interspersed with insignificant lapses of time representing background areas. By my method the character separation 35 is obtained on the receiving screen in accordance with a non-linear control of the horizontal and vertical deflecting circuits.

The field of utility of my news dissemination system can, of course, be extended to cover the 45 transmission of bid and asked prices on stocks, bonds and commodities. The system may also be found useful in communicating details of sporting events, game scores, racing results, betting odds, and word pictures covering any conceivable item of news or other intelligence.

50 My method of storing in tabularly arranged registering devices the effects of price fluctuations within ever widening limits of price range, and then periodically surveying the stored effects, appears to offer a distinct advantage over the heretofore accepted practice of transmitting quotations over a ticker system in respect to each individual market transaction. To certain parties the details of each transaction may be of 55 interest, but to the majority of people who watch the ticker the matter of chief concern is—how does the last quotation on a given item compare with the opening price, the high and the low for the day. Next to that in importance is the 60 question of volume, up to the minute in respect to the transactions in any particular security. If the market is dull, then a tape watcher may have to wait many minutes for a transaction on some particular stock to be quoted, and even 65 then, in the absence of a quotation board, there is no basis of comparison between the last price and previous price range. This difficulty is, therefore, effectively solved by the periodic survey 70 of all market quotations covered by a more 75

or less complete tabulation as obtained through the use of a price storing mechanism. Furthermore, in a very active market, ticker systems of the types now in use are inadequate; so much so that they cannot keep pace with the transactions as made on the exchange. In other words, the limit of speed for code-signaling of the quotations is soon reached and beyond that point inevitable delays of reporting occur. My 10 periodic survey of the active stocks every thirty seconds and of the least active stocks every five minutes is entirely independent of the volume of transactions on the exchange. Hence it never need fall behind the market.

15 In my copending application Serial No. 329,427, filed April 13, 1940, which is a continuation-in-part of the instant application, I have again shown and described a multiplex television system embodying many of the features herein described. The claims of the two applications are, however, believed to be patentably distinct.

I claim:

1. The method of multiplex transmission and reception of television picture images which comprises, assigning adjacent elemental areas of a mosaic to different ones of a plurality of different interwoven pictures, scanning said areas successively and forming an image at the locus of reception in conformity with the light and dark areas of a single one of said pictures.

2. The method of multiplex transmission of picture images and reproduction thereof at different points of reception which comprises, assigning adjacent elemental areas of a mosaic to different ones of a plurality of different interwoven pictures, scanning said areas successively, transmitting a train of signals representative of the light and dark areas of the scanned mosaic and reproducing the different pictures simultaneously at the different points of reception by sorting out the signals respectively appropriate to each picture.

3. In a news disseminating system, a television transmitter including a photo-electric screen, means for projecting on said screen an image of interwoven characters, means for electronically scanning said screen, synchronized means for transmitting and receiving signals representative of the scanned elemental light and dark areas of said image, means for composing a visible image at the locus of reception of said signals, means for selecting a portion of the received signals representative of a desired group of legible characters while rejecting the remainder of said signals representing others of the interwoven characters, and means for causing only the selected signals to control the composition of the received image.

4. In a news disseminating system, a receiver having means for selecting discrete but related elemental portions of a train of signals while suppressing the effects of intervening and unrelated portions of said train, a cathode ray tube having a fluorescent screen and means responsive to the selected portions of said signals for electronically scanning said screen thereby to produce images on said screen, and means for so determining the size of the scanning spot which is projected in response to the selected portions of said signals that areas scanned during the suppression of unrelated portions of the signal train are substantially covered by said spot and the related elemental areas of said images are rendered substantially contiguous.

5. In a system of the class described, television

transmitting apparatus having a screen, means for projecting upon said screen a composite image pattern composed of elemental light and dark areas of which certain non-adjacent elemental areas are pictorially related, while all adjacent elemental areas are pictorially unrelated, television receiving apparatus having a second screen, a device in said receiving apparatus for making a skip-selection of signals emitted by said transmitting apparatus, each selected signal corresponding to an elemental screen area, and means controlled by the selected signals for producing on said second screen an intelligence-bearing image pattern composed of elemental light and dark areas of which adjacent areas are pictorially related to one another, said image pattern being in accordance with a selection of non-adjacent elemental light and dark areas on the first said screen.

6. In a system of the class described, in which a plurality of projectors is focused upon a screen and timing apparatus is used to control the progression of subject matter to be displayed on said screen, the method of display of reading matter on a second screen which comprises selectively illuminating said projectors in different combinations under control of said timing apparatus, retaining the projection on the first said screen of an image for a time period sufficient to read at least a portion of the characters thereon, electronically scanning said image repeatedly for continuously transmitting signals representative of said image, employing a selected portion of said signals constituting an intermittently transmitted array thereof to control the reproduction on the second said screen of a selected portion of the scanned image of the first said screen, and varying at will at the locus of the second said screen the image portion thus selected for reproduction.

7. A multiplex television system having a transmitter, including an image screen, means for interspersing one with another on mutually exclusive portions of said screen different light and dark elemental areas respectively appropriate to different ones of a plurality of independent pictures, and a television receiver operable from signals propagated by said transmitter, said receiver having an image screen and means for reproducing on said screen a selected one of said pictures independently of the others.

8. A multiplex television system in accordance with claim 7 and having means for scanning the transmitting and receiving image screens synchronously and line after line, means for suppressing the effects of unrelated interspersed signals on each scanning line pertaining to the selected one of said pictures, and means for suppressing the effects of unrelated signals throughout the scanning of entire lines of unrelated pictures.

9. The method of transmitting and receiving pictures which comprises, interspersing the elemental picture areas of different picture images, one with another, to form a composite image pattern, converting the varying light intensities of said pattern into trains of electric impulses, separating out for reproduction of a desired picture image the impulses appropriate thereto, and suppressing the effects of those impulses which are inappropriate thereto.

10. The method as defined in claim 11 including the further step of so reproducing the selected picture image that certain of the elemental areas thereof are substantially contiguous while background areas are appropriately introduced be-

70

75

tween certain of the elemental areas the light and dark intensities of which are controlled by successively utilized impulses.

11. In a communication system, means for projecting a composite image representing a plurality of pictures, means for periodically scanning said image, means for transmitting a train of signals representative of said image, receiving means operable synchronously with said transmitting means, said receiving means comprising a device for accepting a skip-selection of said signals which when segregated apart from the entire body of signals is representative of character-images constituting a single one of said pictures and bearing a given piece of intelligence, and means for rejecting interspersed signals representative of non-selected picture elements of said composite image.

12. In a device for the reception of a selected one of a plurality of interwoven picture image patterns, represented by multiplexed image signals, a cathode ray tube having horizontal and vertical scanning means connected thereto, selective means including delay networks for causing the cyclic action of said scanning means to be adjustably timed with respect to synchronizing signals accompanying said image signals, and means under control of said selective means for substantially suppressing the electronic emission in said cathode ray tube during moments of reception of image signals corresponding to unwanted elemental areas of the interwoven picture image pattern.

13. A device in accordance with claim 12, further characterized in that said selective means is operable to control the acceptance of periodically and intermittently received signals representing elemental light and dark areas along a scanning line.

14. A device in accordance with claim 12 and further characterized in that said selective means comprises means operable to control the acceptance of signals to be rendered effective only along certain selected scanning lines of the image area, and means to suppress the effects of signals applicable to the intervening scanning lines.

15. In a system of the class described, means for transmitting picture signals and synchronizing signals, a receiver having a line scanner and a frame scanner, each under control of appropriate ones of said synchronizing signals, said receiver also having an electron gun and a fluorescent screen for composing a picture image whose elemental areas are in accordance with said picture signals, means localized at said receiver for so

controlling the line scanner that the effects of the elemental area signals as projected on said screen by said electron gun are compressed into detached groups along each scanning line, thereby to form vertical image-free bands in the frame area, and means also localized at said receiver for so controlling the frame scanner that the effects of the image signal trains comprehended in successive scanning lines are compressed into detached groups, thereby to form horizontal image-free bands in the frame area.

16. A system in accordance with claim 15 in which the transmitting means includes means for correlating a predetermined plurality of said picture signals as a representation of a single character image, and means at said receiver for so segregating the effects of said correlated picture signals that separate character images are framed by said vertical and horizontal image-free bands.

17. In a communications system, a viewing field, means for simultaneously displaying a plurality of intermeshed intelligence-bearing character images on said field, means for successively scanning adjacent portions of said field, thereby to produce a train of picture signals, terminal apparatus for the transmission of said signals over a channel, receiving apparatus operable synchronously with said terminal apparatus and having means for accepting at least a portion of said signals and for translating the same into facsimile images, and selective means for rendering effective only the received signals which relate to the character images the grouping together of which serves to convey a desired piece of intelligence.

18. In a facsimile communications system, a screen, means for forming character images within the frame area of said screen, each character image being formed in broken outline by a uniform number of discrete horizontal rows of elemental light and dark areas, each row having a uniform number of mutually exclusive and discrete elemental light and dark areas reserved to the use of said character, means for scanning the elemental areas successively, thereby to initiate a train of signals, transmitting and receiving apparatus for utilizing said signals, image reproducing means connected with said receiving apparatus, and means operative under control of said scanning means for compressing each reproduced character image into a discrete portion of said frame area, different character images being thus separated by image-free horizontal and vertical spaces.
